CLAIM

The ornamental design for a display screen or portion thereof with animated graphical user interface, as shown and described.

DESCRIPTION

FIG. 1 is a front view of a display screen or portion thereof with animated graphical user interface showing a first image in a sequence.

FIG. 2 is a second image thereof.

FIG. 3 is a third image thereof.

FIG. 4 is a fourth image thereof.

FIG. 5 is a fifth image thereof.

FIG. 6 is a sixth image thereof; and,

FIG. 7 is a seventh image thereof.

The broken lines show a display screen or portion thereof and form no part of the claimed design.

The appearance of the animated images transitions between the images shown in FIGS. 1-7. The process or period in which one image transitions to another forms no part of the claimed design.
